UNITED STATES PATENT OFFICE

GEORGE SCHAMBERG, OF BUFFALO, NEW YORK, ASSIGNOR TO BUFFALO CO-OPERATIVE STOVE CO., OF BUFFALO, NEW YORK, A CORPORATION OF NEW YORK

HINGE

Application filed April 3, 1928. Serial No. 266,959.

This invention relates to a hinge and more particularly to a concealed hinge which is intended for use in connection with oven doors for enameled stoves, although the same 5 may also be used in other places.

The principal object of this invention is to provide such a hinge which so supports and limits the door in its opening movement that the lower enameled edge thereof cannot come 10 in contact with the stove frame which supports it. It has been found that with enameled stoves, when an enameled surface of a moving part, such as the lower edge of the oven door, comes in contact with another 15 surface, the enamel breaks, cracks and chips, the original chipped portion at the point of contact gradually spreading until a large and unsightly patch of unenameled surface appears on the face of the door. To avoid this, 20 the present hinge is designed to prevent contact between the exposed enameled edge of the door and the stove frame.

Another object is to provide a hinge which is so organized that when the door is opened 25 its inner face forms a continuation of the floor of the oven thereby permitting of sliding the heavy pots and roasters into and out of the oven without having to ride over a shoulder formed by the oven door being higher or lower than the oven floor.

A further aim is to provide such a hinge 30 in which all the hinge parts are formed integrally with either the door or the frame, thereby eliminating the expense of separate castings and facilitating the assembly of the stove as well as eliminating the cost of bolts or other fastenings.

Other purposes are to provide such a hinge 35 which is noiseless, smooth in action, strong and durable and not liable to get out of order, and in which spring means are provided for cushioning the opening movement of the door.

In the accompanying drawings:

Figure 1 is a front view of a stove having an oven door in connection with which the present invention is intended to be employed.

Figure 2 is a vertical section through the door, and frame, the same being taken on line 50 2-2, Fig. 4.

Figure 3 is a vertical section through the oven door, hinge and stove frame, the same being taken on line 3-3, Fig. 4, and showing the oven door fully opened.

Figure 4 is a fragmentary rear view of the 55 door, frame and hinge viewed from the interior of the oven.

Figure 5 is a fragmentary view similar to Fig. 2, but showing a shim applied to the bearing member of the oven when the same 60 has become worn.

Similar reference numerals refer to like parts in each of the figures.

The frame of the stove may be of any suitable construction and as shown includes vertical side bars 10, an upper cross bar 11, and a lower cross bar 12 on which the door 13 of the oven is hinged to swing downwardly and outwardly. Each of these bars is preferably made of cast iron and the oven is enclosed by panels 65 14 in any well known and approved manner. 70

The oven door 13 as shown is made integrally from cast iron and is formed to provide a raised marginal portion 15 and a central panel 16. The door is provided with the 75 usual handle 17 and may have a temperature indicator 18 to indicate oven heat. The entire outer surface of the stove frame and the oven door are coated with enamel and to provide a definite finish line for the enamel at 80 the lower edge of the oven door, the lower edge of the same is provided with a channel 19 which extends between the hinges which are located at the lower corners of the oven door. In applying the enamel, the lower edge 85 of the oven door is enameled up to the channel 19 so that the enamel does not extend around on the rear side of the door where it would be chipped off when the door is closed. Stove enamel is extremely brittle and the 90 original chipped portion would soon spread to the front face of the door and render the same unsightly.

Projecting upwardly from each end of the lower cross bar 12 of the stove frame is an 95 integral bearing member 20 which bearing members pivotally support the oven door. As best shown in Figs. 2, 3 and 5, each of these bearing members 20 is formed to provide a forwardly facing half bearing 21 and the 100

rear side of this bearing member is formed to provide a semicylindrical face 22 which extends from the stove frame to the upper end of the bearing and is substantially concentric with the half bearing face 21 on the front side of the bearing member.

To pivotally support the door on the half bearing 21, the oven door is formed at its lower corners to provide rounded projections 23 which extend downwardly and inwardly therefrom and engage the half bearing 21 on the stove frame. As best shown in Fig. 3, these projections are not circular but each is provided with a downwardly and rearwardly projecting salient portion 24 which engages the half bearing. By the provision of this salient portion, the front face of each of the rounded projections 23 at no time comes in contact with the half bearing, and should this part of the projection be enameled, the same will not become chipped with consequent spreading of the chipping to the face of the oven door.

To guide the oven door in its pivotal movement and also to hold the projection 23 in engagement with the half bearing 21, arms 25 are formed integrally with the oven door and project downwardly and inwardly therefrom. Each of these arms 25 is curved and is formed to provide a semicylindrical face 26 which engages the semicylindrical face on the rear or inner side of the bearing member 20. By this means in all positions of the door, the projection 23 is held in proper engagement with the front half bearing 21, and the door cannot be lifted or moved out of place.

To prevent movement of the oven door beyond a horizontal position and also to prevent the front face of the door from coming in contact with the lower cross bar 12 with consequent marring of the enamel each time the door is lowered, a stop 27 is formed on the lower or outer end of the guiding arm 25, this stop engaging the side flanges 28 projecting inwardly from the side bars 10 of the stove frame when the door is lowered to its horizontal position shown in Fig. 3. These flanges 28 also serve to limit the inward movement of the door when it is closed.

To cushion the downward movement of the oven door and avoid the danger of breakage of any of the cast metal parts should the door be accidentally dropped when opening the same, a helical spring 29 is secured at its upper end to each of the stop projections 27, and at its lower end is suitably secured to the stove frame. It is apparent that as the door lowers and the stop projection 27 is elevated, the helical spring 29 is stretched to yieldingly prevent the door from dropping.

Should the half bearing 21 or the projection 23 become worn through constant use, a split sleeve or shim 30 may be slipped over each 65 of the projections 23, as best shown in Fig. 5.

By this means the wear at the pivotal connection between the oven door and the stove is compensated, and the hinge will continue to function noiselessly and smoothly. Such replacement would be, of course, exceptional. 70

It will be noted that the hinge is so designed that at no time does the enameled surface of the oven door and frame come in contact with a moving part and the same will therefore be preserved in good condition. 75

This hinge is also strong, durable and all parts of it are cast integrally with the oven door or stove frame, thereby materially reducing manufacturing costs. It is also smooth and noiseless in action and will not get out of order under severe use.

I claim as my invention:

1. A hinge for a door supported on a frame including a bearing member on said frame, said bearing member being formed to provide a half bearing on its outer side and having a cylindrical concentric surface on its rear side, a rounded projection on said door engaging said half bearing, a guiding arm projecting rearwardly from said door and having a semicylindrical surface engaging the semicylindrical rear face of said bearing member, and means for limiting the movement of said door. 85

2. A hinge for a door supported on a frame including a bearing member projecting upwardly from the lower edge of said frame, said bearing member being formed to provide a forwardly facing half bearing and having a concentric semicylindrical surface on its rear side, a rounded projection projecting downwardly and inwardly from the lower edge of said door and engaging said half bearing, a guiding arm projecting rearwardly and downwardly from said door and having a semicylindrical surface engaging the rear face of said bearing member thereby to guide said door in its pivotal movement, means for limiting the pivotal movement of said door and spring means exerting a downward and rearward pressure against said door whereby said projection is held against said forwardly facing half bearing in all positions of said door. 100 110

3. A hinge for a door supported on a frame including a bearing member projecting upwardly from the lower edge of said frame, said bearing member being formed to provide a forwardly facing half bearing and having a concentric semicylindrical surface on its rear side, a projection projecting downwardly and rearwardly from the lower edge of said door, said projection having a salient portion on its rear side which salient portion engages said half bearing thereby to prevent contact between the exposed surfaces of said door and said frame, a guiding arm projecting downwardly and rearwardly from said door and having a semicylindrical surface engaging the rear face of said bear- 115 120 125 130

ing member thereby to guide said door in its pivotal movement, and means for limiting the pivotal movement of said door.

4. A hinge for a door supported in a frame including a bearing member formed integrally with said frame and projecting upwardly therefrom, said bearing member being formed to provide a forwardly facing half bearing and having a concentric semi-cylindrical surface on its rear side, a projection formed integrally with said door and projecting downwardly and rearwardly from the lower edge thereof to engage said half bearing, a curved guiding arm formed integrally with said door and projecting downwardly and rearwardly therefrom and having a semicylindrical surface engaging the rear face of said bearing member thereby to guide said door in its pivotal movement, and a spring connected with the end of said guiding arm and exerting a downward and rearward pressure thereon in all positions of said guiding arm whereby said projection is held against said forwardly facing half bearing in all positions of said door.

25 In testimony whereof I hereby affix my signature.

GEORGE SCHAMBERG.
